UNITED STATES PATENT OFFICE.

GEORGE FURUHOLMEN, OF MINNEAPOLIS, MINNESOTA.

FURNACE.

1,132,573.

Specification of Letters Patent.

Patented Mar. 23, 1915.

Application filed January 9, 1913. Serial No. 740,968.

To all whom it may concern:

Be it known that I, GEORGE FURUHOLMEN, a subject of the King of Norway, residing at Minneapolis, in the county of Hennepin and State of Minnesota, have invented certain new and useful Improvements in Furnaces, of which the following is a specification.

My invention relates to improvements in furnaces, and has for its object to provide a furnace having an improved construction and arrangement of fuel-feeding and sustaining mechanism in combination with means for directing and controlling the fuel gases and air so that a coking effect is had upon the fresh coal fed into the furnace and the fuel gases are mixed with the air at a point where the temperature of the furnace is the highest, so that practically complete combustion immediately takes place and a smokeless, or nearly smokeless combustion results.

It is a further object of my invention to provide means for feeding the coal from the rear to the front of the furnace chamber and to provide mechanism for receiving the unconsumed material at the end of the feeding mechanism and pushing said unconsumed material forward at the same time that ashes and waste are permitted to drop through into the ash pit.

It is a further object of my invention to provide means for regulating the rate of feed of coal from the coal feeding chamber to the moving grate and the thickness of the body of coal upon said grate, and also to provide means for regulating the extent of grate surface subjected to draft, all for regulating and varying the intensity of the fire in the furnace.

The full objects and advantages of my invention will appear in connection with the detailed description thereof and are particularly pointed out in the claims.

In the drawings, illustrating the application of my invention in one form,--Figure 1 is a sectional side elevation of a furnace embodying my improvements. Fig. 2 is a transverse section on line 2--2 of Fig. 1. Fig. 3 is a view similar to Fig. 1 illustrating a modified means of forcing the coal from the primary feeder to the grate. Fig. 4 is a

longitudinal section of a part of a furnace showing my improvements applied to a different type of boiler. Fig. 5 is a section on line 5--5 of Fig. 4. Fig. 6 is a sectional view across the front grate taken through the main receiving part of the grate and outside of one of the movable forwarding members. Fig. 7 is a similar sectional view taken in part through one of the movable forwarding members. Fig. 8 is a sectional view through a portion of the grate along the grate shaft taken on line 8--8 of Fig. 6. Fig. 9 is a plan view of a portion of the receiving grate. Fig. 10 is an enlarged sectional view of the front part of the receiving grate taken on line 10--10 of Fig. 6.

In the practice of my invention the primary elements or features thereof are,--a feed chamber 11 located adjacent the rear part of the fire box 12 opening thereinto through a passage-way 13, a moving grate 14 having the rear turn thereof adjacent the opening 13 and the upper surface constantly moving toward the front of the furnace, a coking arch or baffle 15 extending forwardly above the said moving grate to a point above and a little short of the forward end of said grate, a damper plate 16 below the fuel-receiving portion of the grate for withholding air from a part of the fuel on said grate, and a combination dumping and fuel-forwarding grate mechanism 17 at the front of said moving grate for receiving the unconsumed material from the grate and sifting and forwarding the same to the front of the furnace or dumping, as desired.

In the application of my invention shown in Figs. 1 and 3, the feed chamber 11 may conveniently be located back of the wall 18 which supports the front end of the boiler, while for the type of boiler illustrated in Fig. 4 the chamber 11 may be formed at a suitable point beneath the boiler by a specially devised brick-work structure 19. In either event the coal or other fuel passes by gravity or is forced through the opening 13 by automatic stoking mechanism upon the rear end of endless grate 14. At once upon passing to the grate 14 the coal is subjected to heat and will begin to emit gases. If, however, these gases were allowed to escape directly into the combustion

chamber at this point and to flow thence toward the stack, gases would enter the combustion chamber at a low temperature where the combustion chamber itself was at a relatively low temperature, and a seriously wasteful and obnoxiously smoke-producing fuel consumption would result. I provide, therefore, a baffle arch 15 extending forwardly within the fire box 12 from above the fuel admission passage 13 to a point at nearly the end of the moving grate. All gases freed from the fuel upon the grate 14 must flow into the fire box 12 over the forward edge 20 of the baffle 15. This point is directly above the hottest part of the fire and the baffle arch 15 at its front edge will be heated red or white hot, so that the gas emitted from the incoming fuel escapes into the fire box at the hottest point thereof. Moreover, the entire baffle arch 15 is subjected to the heat of the furnace from above as well as from below and will necessarily become very hot. The gases from the incoming fuel flowing along this hot surface will become highly heated before escaping over the incandescent edge 20 of the baffle arch. By means of the damper 16 air is permitted to pass through only the forward portion of the grate, so that a large part of the fuel upon the grate beneath the baffle arch 15 is subjected to heat such as will drive off the gases therefrom and effectively coke the fuel before actual combustion takes place as the fuel reaches the forward half of the grate. The air draft passing through the forward portion of moving grate 14, and through the forwarding and dumping grate 17, not only provides the hottest combustion of the fuel beneath the end 20 of baffle arch 15, but also mixes with the gases previously liberated from the fuel below the end 20 of the baffle arch where both gas and air are heated to a very high temperature, which results in such complete oxidation of the fuel gases that the products of combustion are practically smokeless.

Preferably I form the damper 16 in two sections, one of which is movable to increase or decrease at will the surface exposed to draft at the forward part of moving grate 14, a will hereinafter be described, in the form of my device shown in Fig. 1, which is a highly useful and satisfactory feeding method, the rear portion of moving grate 14 extends beneath the opening 13 and the bottom of feed chamber 11, so that it is only necessary to keep the chamber 11 stoked with coal in order that the moving grate 14 shall continually feed forward the desired amount of fuel. To vary the thickness of the sheet of fuel fed upon moving grate 14 for the purpose of changing the heat of the fire, I provide a vertical slid-

able gate 21 back of the wall 18 and projecting into the passage-way 13. Said gate is provided with rack 22, with which mesh spur gears 23 on a shaft 24 extending outside of the side wall 25 of the furnace, said extending portion having thereon a hand wheel 26. By turning the hand wheel the gate 21 may be moved so as to raise or lower the portion extending into passage-way 13 and correspondingly increase or diminish the thickness of the sheet of fuel fed forward by the endless grate 14. In Fig. 3 a mechanical stoker 27 of a common pusher type is shown for forcing the fuel from feed chamber 11 through passage-way 13 and upon endless feeder 14. When the mechanical stoker is used the endless feed grate 14 will not extend so far rearwardly as in the form shown in Fig. 1, and a guide plate 28 will carry the coal to the top of the endless feeder. Another form of mechanical distributing mechanism is shown in Figs. 4 and 5 in which fuel is distributed from a side hopper 29 into the feed chamber 11, and from thence forced upon the endless feed belt 14 by means of a spiral conveyer 30, preferably of diminishing diametrical dimensions as shown, in which case a guide plate 31 similar to the guide plate 28 may be arched around and above the spiral conveyer 30 so as to direct the fuel forced upon said plate by the said spiral conveyer through the passageway 13 and upon the moving grate 14. The mechanical stokers shown are referred to as typical of different mechanical operating devices for the purpose. When such devices are used the supply of fuel to the moving grate may be regulated by varying the rate of operation of the mechanical stoker.

It is to be noted that the modifications shown in Figs. 3 and 4 relate only to the means of supplying the sheet of fuel to the moving grate. As shown in Fig. 3, a mechanical stoker involving reciprocating pushers below hopper 11 is employed, which pushes force the fuel upon moving grate 14. As shown in Fig. 4, the same result is obtained by an endless screw 30 which may project from a hopper 29 at one side of the furnace, as shown in Fig. 5. In either of these last mentioned forms the fuel is positively forced upon the moving grate by the mechanical means shown which require a motor for operating the same; while in the form shown in Figs. 1 and 2, the moving grate 14 extends below the mouth of hopper 11 and the feed of the fuel to said grate is effected by gravity.

The grate mechanism is supported upon a frame comprising side bars 32 and end bars 33, said side bars having rollers 34 journaled thereon so that if desired the frame may be dropped upon tracks 35 and

withdrawn from the furnace through an opening in the front wall thereof provided for that purpose. Normally the front end of the frame is sustained upon posts 36, and the rear end upon screw members 37 in a position sloping from the front to the rear, the screw members 37 providing means for adjusting the rear end of the frame. Upon a rear shaft 38, journaled between side members 32, is a solid roller 39, and similarly journaled between side pieces 32 near the front end thereof, is a shaft 40, preferably supplied with a series of narrow rollers 41. The endless grate 14 consists of a chain 15, grate formed of transverse bars having draft openings through the same and extending over roller 39 and the sets of rollers 41. Both shafts 38 and 40 may be provided with worm wheels 42, with which mesh a pair of worms 43 upon a shaft 44 constantly driven from any desired source of power by which the roller 39 and rollers 41 are rotated at a uniform speed and the endless chain grate 14 continuously and automatically moved from the rear toward the front of the fire box.

The damper 16 comprises a fixed plate 45 supported upon cleats on side pieces 32 and a crossbar 46 adjacent roller 39, said plate 45 having the end 47 thereof in close proximity to the periphery of roller 39 so as to close draft communication from below damper plate 45 through the grate 14. Secured to crossbar 46 and another crossbar 48 toward the forward portion of grate bar 14, are longitudinal bars 49 upon which slide a movable damper plate 50, said plate being provided on the under side thereof with racks 51, which are engaged by pinions 52 on a shaft 53 journaled in side pieces 32, said shaft 53 extending beyond side piece 32 between worm wheels 42 on shafts 38 and 40, and having on the extended end thereof a hand wheel 54. By turning the hand wheel 54 the movable damper member 50 will be slid backward or forward relative to baffle arch 15, opening more or less of the fuel supporting portion of moving grate 14 to draft of air from beneath.

The front receiving and forwarding grate 17 comprises a stationary portion 55 held in fixed position at the front of the furnace, said portion 55 being formed with draft openings 56 and 57. Between the fixed grate portion 55 and the peripheral curve of moving grate 14, where the same goes over rollers 41, is located a grate section 58, said section comprising a front apron 59 formed with a series of draft openings 60 therein and a series of depending ribs 61, crossbars or webs 62 at the rear of said ribs, and a crossbar 63 at the front thereof operating to bind the same rigidly together at the lower portion thereof. The ribs 61 are provided with circular apertures 64, through which extends loosely a squared, hollow shaft 65 having the corners rounded so that the same may rotate in the said apertures 64. The upper front portions of ribs 61 are formed as indicated at 66 so as to engage the fixed grate member 55 and prevent the forward portion of plate 59 from contacting with the curved portion of moving chain grate 14. It is to be noted that the grate section 58 and the fixed section 55 are jointly formed so as to provide a hollow or depressed portion 67, extending rearwardly in a curved ascending plane into close proximity with the descending portion of moving grate 14. Back of apron 59 and between ribs 61 are positioned a series of grate bars 68 fast on shaft 65 and movable in unison by such shaft. It is noted that the grate bars 68 are formed with a curved upper surface corresponding to that of the ribs 61, and also each of said grate bars is provided with transverse draft apertures 69 and longitudinal draft apertures 70, formed between pairs of forwardly extended ribs 71 which come into proximity to projecting portions of fixed grate 55 and are adapted to engage and crush clinkers or other obstructions which may get on to the grate bars 68. The rear portion of the grate bars 68 is formed as an extended arcuate flange 72, as best shown in Figs. 6 and 7. Material upon the grate and within the depressed portion 67 will be pushed in a forward direction when the grate sections 68 are rocked upwardly; and material upon the apron 59 will be restrained from falling through between ribs 61 by aforesaid flanges 72.

From the above it will be seen that the grate bars 68 are secured to move together upon and with the shaft 65. On one of said grate bars is formed a forwardly projecting crank arm 73, to the farther end of which is connected an operating link or bar 74 which projects through the front of the furnace and is pivotally connected to an operating lever 75. By this means the shaft 65 may be rocked in a direction to cause the grate bars 68 to rise between the adjacent ribs 61, the operative portions 76 of said bars moving upwardly and forwardly so as to push the material resting above the hollow portion 67 of the grate toward the front of the fire box, the loose ashes and clinkers dropping through between the rear portions of ribs 61. Clinkers that are too large to pass between said ribs 61 will be engaged between the ends of ribs 71 and portions of the fixed grate 55, and by operative portions 76, said clinkers thereby being broken so that they will fall through. One of the depending ribs 61 is provided with an integral downwardly and forwardly projecting crank arm

77 which is positioned adjacent the crank arm 73. To the lower end of crank arm 77 is connected an operating bar or link, which projects forwardly through the front side of 5 the furnace and is pivotally connected to an operating lever, 79. By operating the lever 79 the grate plate 58 may be swung upwardly and forwardly, dumping the contents thereon into the ash pit. Preferably 10 in accomplishing the dumping action the grate 58 and the grate bars 68 will be operated simultaneously through levers 73 and 77.

The grate section 58 and the shaker bars 15 68 taken together constitute not only means for shaking or dumping the ashes, but a true grate having a multiplicity of draft spaces for providing complete and effectual draft to the material located upon this grate.

20 The fixed grate section 55 also provides ample draft spaces. The purpose of this arrangement, therefore, is to provide a proper grate surface for receiving and retaining unconsumed material from the moving grate 25 14 and supplying the requisite drafts of air to effect proper combustion of such material, as well as shaking and dumping mechanism. Moreover, the shaking device has a peculiar and novel function, namely—to move the 30 material on the grate from the rear thereof toward the front so that the most fully consumed fuel and ashes will be continually pushed to the front of the grate adjacent the furnace opening and farthest from the 35 boiler, where, for convenience of operation and from the standpoint of practical economy, it is desirable to have a relatively low temperature.

It is to be noted that my entire organization 40 provides a fuel distributing and draft mechanism not only efficient in a high degree for producing practically smokeless combustion, but also of unusual convenience to the fireman or operator, who always will have 45 a clear view of the fire bed and has convenient and ready access to all operating parts of my device. It is also true that the arrangement of moving grate, fuel supply, hopper or box admission, passage-way to the 50 moving grate and baffle arch above the moving grate are assembled in a relative position such as to give the best possible results. The baffle arch must be spaced a sufficient 55 distance above the coal upon the moving grate to permit ready movement of gases freed from said coal toward the end 20 of the baffle arch. Preferably also, as shown, the baffle arch should be inclined upwardly. This baffle arch will not prove effective for 60 the purpose if made too long, and for this reason it is impracticable to use a baffle arch and a moving grate where said arch and grate extend to the rear end of a boiler of any considerable length. The draft control-

ling apparatus below the moving grate is 65 absolutely essential to draft regulation so that the hot part of the fire will be at the forward end of the moving grate and below the end 20 of the baffle arch. If a thin sheet 70 of coal is to be fed for keeping a comparatively low fire, and no damper mechanism were provided, the fire would creep back beneath the baffle arch to the coal admission point, and even might finally reach the fuel in the supply hopper. The same result 75 would follow to a less degree if a thicker sheet of fuel were fed. A combustion on the moving grate beneath the baffle arch at a point much to the rear of the end 20 thereof is not desirable, since it would be wasteful 80 and be liable to cause smoking.

I claim:

1. A furnace comprising a fire box and a grate therein continuously moving from the rear to a point near the front of the fire box, 85 means for continuously delivering fuel upon the rear end of said moving grate, means above the grate for causing the gases liberated from the fuel to be delivered into the combustion chamber near the forward end 90 of the grate, means below the grate for limiting the delivery of air through the grate to a point approximately below the point of delivery of said gases, and a normally stationary grate at the front of and within 95 the fire box positioned to receive and hold material from the moving grate for further combustion at a point which is close to the hottest, portions of said combustion chamber. 100

2. A furnace comprising a fire box and a grate therein continuously moving from the rear to a point near the front of the fire box, means for continuously delivering fuel upon the rear end of said moving grate, a baffle 105 arch above said moving grate extending forwardly so that the gases released from the fuel on the grate will be delivered into the combustion chamber at a point approximately above the forward end of the moving grate, a draft plate below the moving grate for limiting air draft through the front portion only of the same to produce the hottest combustion area in the fire box at the front of the moving grate and below 115 the end of said baffle arch, and a normally stationary grate at the front of and within the fire box positioned to receive and hold material from the moving grate for further combustion at a point which is close to the 120 hottest portions of said combustion chamber.

3. A furnace comprising a fire-box, a solid roller outside of the rear of said fire-box, a sectional open roller within and near the 125 front of said fire-box, an endless grate continuously moving on said rollers from the rear to the front of the fire-box and com-

prised of a series of supporting bars each formed with a multiplicity of draft openings, an imperforate plate extending from the solid roller to a point near the open roller below the moving grate, a baffle arch extending from the rear of the fire-box to a point forward of the imperforate plate and to the rear of the open roller, and means to supply fuel to the moving grate.

10 4. A furnace comprising a fire box and a grate therein continuously moving from the rear to a point near the front of the fire box, means for supplying fuel to the moving grate, a normally stationary grate at the 15 front of and within the fire box positioned to receive and hold the material from the moving grate for further combustion at a point which is within the hottest combustion portion of the fire box, said stationary 20 grate being of considerable area and being located below the delivery portion of the moving grate, and means forming a portion of said stationary grate for engaging and forwarding material thereon to the extreme 25 front portion of the fire box.

5. A furnace comprising a fire-box, a solid roller outside of the rear of said fire-box, a sectional open roller within and near the front of said fire-box, an endless grate continuously moving on said rollers from the rear to the front of the fire-box and comprised of a series of supporting bars each formed with a multiplicity of draft openings, an imperforate plate extending from the solid roller to a point near the open roller below the moving grate, a baffle arch extending from the rear of the fire-box to a point forward of the fixed plate and to the rear of the open roller, means to supply fuel 40 to the moving grate, and a normally stationary grate at the front of and within the fire-box having a portion thereof extended rearwardly so as to provide an upwardly curved surface for receiving material from 45 the moving grate where the same passes about the open roller.

6. A furnace comprising a fire-box, a solid roller outside of the rear of said fire-box, a sectional open roller within and near the front of said fire-box, an endless grate continuously moving on said rollers from the rear to the front of the fire-box and comprised of a series of supporting bars each formed with a multiplicity of draft openings, an imperforate plate extending from the solid roller to a point near the open roller below the moving grate, a baffle arch extending from the rear of the fire-box to a point forward of the fixed plate and to the 60 rear of the open roller, means to supply fuel to the moving grate, and a normally stationary grate at the front of and within the fire-box having a portion thereof extending rearwardly so as to provide an upwardly-

curved surface for receiving material from 65 the moving grate where the same passes about the open roller, said relatively stationary grate having all portions thereof provided with a multiplicity of draft openings and forming, together with the front 70 upper portion of the moving grate, the combustion area within the fire-box.

7. A furnace comprising a fire box, and a grate therein continuously moving from the rear to a point near the front of the fire box, 75 means to supply fuel to the moving grate, a normally stationary grate at the front of and within the fire box positioned to receive and hold material from the moving grate for further combustion at a point 80 which is within the hottest portion of the fire box, said stationary grate comprising a fixed section and a relatively movable dumping section, all parts of said sections being provided with a multiplicity of draft openings, and means forming a part of the 85 dumping section for engaging and forwarding material thereon upon and against the fixed section.

8. A furnace comprising a fire-box and a 90 grate therein continuously moving from the rear to a point near the front of the fire-box, means to supply fuel to the moving grate, a receiving grate within the fire-box and in front of the moving grate, said receiving 95 grate comprising a fixed section and a relatively movable dumping section, said dumping grate comprising a main receiving portion provided with a series of elongated slotted openings extending through the 100 dumping grate to the fixed grate bars, and a series of movable perforated bars lying within said slots and in one position, forming a part of the receiving surface of the dumping grates but when oscillated having 105 a portion thereof projected above and forwardly along said surface to engage and forward material upon and against the fixed grate.

9. A furnace comprising a fire-box and a 110 grate therein continuously moving from the rear to a point near the front of the fire-box, means to supply fuel to the moving grate, a receiving grate within the fire-box and in front of the moving grate, said receiving grate comprising a fixed section and a relatively movable dumping section, said 115 fixed section being at the front of the receiving grate and adjacent the fire-man's door into the fire-box and means forming a 120 part of the dumping section for engaging and forwarding material thereon upon and against the fixed section.

10. A furnace comprising a fire-box and a grate therein continuously moving from 125 the rear to the front thereof, means to supply fuel to the moving grate, a receiving grate at the end of the moving grate com-

prising a dished surface, said receiving grate including movable grate bars for engaging and forwarding fuel on the receiving grate, said movable bars having arcuate flanged rear portions to prevent material falling through the receiving grate at the rear part thereof when said bars are operated.

In testimony whereof I affix my signature in presence of two witnesses.

GEORGE FURUHOLMEN.
